UNITED STATES PATENT OFFICE

93,535

DESIGN FOR A CIGARETTE CASE OR ANALOGOUS ARTICLE

Monroe Block, Providence, R. I., assignor to Monroe Block & Co., Providence, R. I., a partnership composed of Monroe Block and William
A. Shawcross

Application July 19, 1934, Serial No. 52,640

Term of patent 7 years

To all whom it may concern:

Be it known that I, MONROE BLOCK, a citizen of the United States, residing at Providence, county of Providence, State of Rhode Island, have invented a new, original, and ornamental Design for a Cigarette Case or Analogous Article, of which the following is a specification, reference being had to the accompanying drawing, forming a part thereof.

In the drawing:

I claim:

The ornamental design for a cigarette case or analogous article, substantially as shown.

MONROE BLOCK.
